(57) **CLAIM**

We claim the ornamental design for an in-vehicle radar with camera, as shown and described.

DESCRIPTION

FIG. 1 is a top-left perspective view of an in-vehicle radar with camera.

FIG. 2 is a bottom-left perspective view of the in-vehicle radar with camera.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The in-vehicle radar with camera is used by being mounted, for example, on a windshield of an automobile. The in-vehicle radar with camera irradiates an object outside the automobile with a radar beam, receives a radar reflection beam from the object, and takes a picture of the object outside the automobile by the camera.
